UNITED STATES PATENT OFFICE.

CHARLES H. SNIDER, OF CONWAY, SOUTH CAROLINA.

ENVELOP.

1,044,935.

Specification of Letters Patent. Patented Nov. 19, 1912.

Application filed February 4, 1911. Serial No. 606,663.

To all whom it may concern:

Be it known that I, CHARLES HUDSON SNIDER, a citizen of the United States, and resident of Conway, Horry county, State of 5 South Carolina, have invented certain new and useful Improvements in Envelops, of which the following is a specification.

This invention relates to improvements in envelopes, and its objects are first to provide 10 a safety device whereby it will be practically impossible to detach the closure flap without mutilating the same.

Another object is the provision of a rupturing tongue formed with the closure flap 15 and so positioned that it may be readily taken hold of by the operator and detached from the sealing flap whereby an opening will be presented to permit the ready insertion of the finger, or the like, to effect an 20 opening along one edge of the envelop.

The above and other objects will be better understood from the following description, taken in connection with the accompanying drawings, in which—

25 Figure 1 is an elevation of an envelop constructed in accordance with my invention and showing the same closed and sealed; Fig. 2 is a similar view of the sealing flap raised; Fig. 3 is a detail showing the free 30 end portion of the rupturing tongue partly raised; and Fig. 4 is a detail showing the rupturing tongue wholly raised and the weakened edge partly broken.

The envelop comprises the front or body 35 portion 5, the end flaps 6 and 7, the bottom flap 8, and sealing flap 9. The end flaps 6 and 7 are formed in the usual manner and arranged over the inner face of the front or body 5. The bottom flap 8 is bent 40 over the inner face of the front or body 5 and as usual has marginal portions bearing on marginal portions of the end flaps 6 and 7, such bearing portions being suitably gummed and sealed. Instead of gumming 45 the entire free edge portion of the sealing flap 9, as is usual in most envelopes, I apply gum on portions of the closure flap located on either side of the medial portion of the free side thereof. With this construc- 50 tion, the medial portion of the free side of

the sealing flap will be free when the sealing flap is sealed as shown in Fig. 1, but may be readily raised by taking hold of the same with the finger and thumb.

In order to facilitate the opening of the 55 envelop, I form the sealing flap with a rupturing tongue 10. This rupturing tongue includes that portion of the sealing flap located between the weakened lines 15 and 16, the said weakened lines 15 and 16 extend 60 from the free edge of the flap to the inner or connected side thereof. The weakened lines 15 and 16 terminate in weakened lines or scoring 17 and 18, these last named weakened lines or scoring 17 and 18 being located 65 in the side edge of the envelop and extending outwardly to the ends thereof. With this construction, the envelop, when sealed, may be readily opened by taking hold of the free end of the rupturing tongue and drawing 70 the same toward the connected end thereof until the rupturing tongue is wholly raised as shown in Fig. 4, after which the finger may be inserted into the disclosed opening and moved through either of the 75 weakened portions 17 or 18. By providing the weakened lines 15 and 16, comparatively no effort will be required to disengage the rupturing tongue and by eliminating gum 80 from the free end portion of the tongue, 85 the said free end portion may be readily engaged between the finger and thumb.

By referring to the drawings, it will be seen that the gummed portions 13 and 14 of the closure flap are perforated as shown 85 at 19. This arrangement of perforations need not be identical to that shown, since it is obvious as will presently appear, that the required effect may be obtained by forming slits in the gummed portions. By the provision of the perforations, it will be practically impossible to disengage the gummed portions of the sealing flap without mutilating the same, and in so doing, it will indicate that the envelop has been tampered 90 with.

Having thus described the invention, what is claimed is:

An envelop having a closing flap hinged to its body portion along one edge thereof, 100

and the hinged edge having perforated side portions and an unperforated intermediate portion, and said flap being provided with a middle ungummed portion and laterally arranged gummed portions along its free edge, and lines of perforations arranged on opposite sides of said ungummed portion and extending to and uniting with the per-

forations in the hinged edge, as and for the purpose described.

10

In testimony whereof I affix my signature in presence of two witnesses.

CHARLES H. SNIDER.
